UNITED STATES PATENT OFFICE.

GOO KOON WO, OF HONOLULU, TERRITORY OF HAWAII.

ADJUSTABLE GO-CART.

1,241,183.

Specification of Letters Patent. Patented Sept. 25, 1917.

Application filed February 26, 1917. Serial No. 151,027.

To all whom it may concern:

Be it known that I, Goo Koon Wo, a citizen of the United States, residing at Honolulu, Territory of Hawaii, have invented certain new and useful Improvements in Adjustable Go-Carts, of which the following is a specification, reference being had to the accompanying drawings.

This invention relates to an improved adjustable go-cart and has for its primary object to provide means for vertically adjusting the body of the cart to an elevated position above the wheel supported frame.

It is another and more particular object of my invention to provide a go-cart having a fixed body section and a vertically movable body section, a plurality of links connecting the opposite ends of the latter body section to the frame, and manually operable means to actuate said links and raise or lower said body sections.

It is a further general object of my invention to improve and simplify the construction of vehicles of the above character whereby the same are rendered highly serviceable and convenient in practical use, durable in construction, and capable of manufacture at relatively small cost.

With the above and other objects in view, my invention consists in the novel features of construction, combination and arrangement of parts to be hereinafter more fully described, claimed and illustrated in the accompanying drawings, in which,

Figure 1 is a side elevation of a go-cart or perambulator showing the movable body section in its lowered position;

Fig. 2 is a similar view showing said body section raised or elevated and the hood extended;

Fig. 3 is an end elevation;

Fig. 4 is a perspective view of the rack dog; and

Fig. 5 is a detail section taken on the line 5-5 of Fig. 1.

Referring in detail to the drawing, 5 indicates spaced channel bars which constitute the longitudinal side walls of a frame, and between these channel bars, at one of their ends, the transverse brace bar 6 is engaged and rigidly secured thereto by bolts or other similar fastening devices. At their opposite ends, the bars 5 are also connected to each other by a cross bar 7, the ends of which are angularly extended, as at 8, and disposed against the outer side of the frame

bars 5. The lower ends of the vertical portions of a suitable handle 9 are disposed against the inner sides of the bars 5, and said handle secured to the bars 5 and the ends 8 of the cross bar by the bolts indicated at 10.

To the under side of each of the frame rails 5, the spring bars 11 are arranged in spaced relation to each other and rigidly fixed at one of their ends to said rails. In loops or eyes 12 formed upon the free ends of the corresponding bars 11, the axles 13 are mounted, and upon the extremities of each axle the ground wheels 14 are supported.

Between the forward ends of the rails 5, a fixed body section 15 is arranged, said body section being rigidly secured to the rails by means of suitable bolts indicated at 16.

Spaced rods or shafts 17 and 18 respectively, are mounted at their ends in the frame bars 5. The rod or shaft 18 is rotatably supported, and upon the same, adjacent its ends, the lower ends of links 19 are loosely engaged. A second pair of links 20 are also fixed at their lower ends upon this shaft. Similar links 21 are loosely mounted upon the ends of the shaft 17. The upper ends of the links 20 and 21 are pivotally connected to the relatively opposite ends of a rectangular frame bar 22. 23 designates angle bars upon which the angular flanges 25 on the lower edges of the side walls 24 of a vertically movable body section, are mounted and secured. The floor or base 26 of this movable section of the body is also secured to these angle bars. Links 27 and 28 are pivotally connected at their upper ends to the relatively opposite ends of each of the angle bars 23. The lower ends of the links 27 and the upper ends of the links 19 are connected to each other by bolts 29 which are loosely engaged for longitudinal movement in slots 30 provided in the longitudinal portions of the frame bar 22. Links 20' also have their upper ends engaged upon the pivots of the link 27 connecting the same to the angle bars 23 and the lower ends of the links 20' and the upper ends of the links 20 are connected to the frame 22 by the pivot bolts 20a. The lower ends of the links 28 and the upper ends of the links 21 are pivotally connected to one end of the bar 22 by the bolts 31. The side walls 24 of the movable body section are cut away at one of

90

95

100

105

110

their ends, as indicated at 32, and provided with upwardly and rearwardly curved, attenuated portions 33. A sector-shaped hood 34 is pivotally mounted upon the rear ends 5 of the angle bars 23, as shown at 35, and the side walls of this hood are each provided with a slot 36 extending in concentric relation to the pivot 35. Bolts or guide pins 37, fixed in the extensions 33 of the side walls 10 24, are engaged in these slots.

To one end of the shaft 18, a lever 38 is fixed, and to said lever, adjacent its other end, one end of a curved rack bar 39 is secured, the teeth 40 of said bar being adapted 15 to co-act with the tooth or point 41 of a locking dog 42. The end of this locking dog is cut away or recessed on one face as at 43, and the rack bar 39 moves between this recessed face and the adjacent frame bar 5. 20 The dog 42 is pivotally mounted upon a stud bolt 44 fixed in the frame bar 5. Adjacent to the dog 42, a substantially triangular-shaped plate 45 is pivotally mounted in the bar 5, as at 46. One end of a short rod 47 is 25 loosely connected to this plate and the other end thereof is pivotally connected to the dog 42, as at 48.

In the operation of the device as above described, when it is desired to elevate the 30 movable body section of the carriage or go-cart from the position shown in Fig. 1 to the position shown in Fig. 2, the lever 38 is forced forwardly and downwardly, thereby raising the links 20 fixed upon the shaft 18 and also forcing the frame 22 upwardly. The links 19 and 27 will thus be spread apart as well as the links 21 and 28, so that the movable body section will be raised 35 above the frame 22 by the links 27 and 28. 40 The links 20 and 20' are moved slightly past the perpendicular and at an opposite angle with respect to the links 19 and 27, as seen in Fig. 2. When the lever is in substantially horizontal position, the movable 45 body section will have been raised or elevated to its full extent, and the dog 42 will engage the teeth of the rack bar 39 to sustain the body section in its elevated position. When it is desired to lower the movable body section, the end of the lever 38 is depressed slightly and the plate 45 moved to withdraw the teeth of the dog 42 from engagement with the rack teeth 40. The movement of the lever is then reversed so 50 that the pairs of links 19 and 27, and 20 and 20' are folded upon each other in relatively opposite directions and the frame 22 and the movable section of the vehicle body lowered upon the wheel supported frame. 55 To each of the side walls 24, a stud bolt 49 is fixed, and upon these stud bolts, arms 50 are loosely mounted at one of their ends and adapted to be securely clamped in an adjustable, angular position by suitable nuts 60 51 threaded upon said bolts. A third bar

52 is also fixed to each of the arms 50 and additional arms 53 are pivoted to the ends of said bars. Links 54 pivotally connected to each other as at 55, connect the arms 50 and 53, whereby the arms 53 may be folded relative to the arm 50. These pivotally connected and adjustably mounted arms provide means for supporting a canopy or shade which may be arranged and secured thereon in any preferred manner.

56 designates an end gate for the fixed body section 15 which is adapted to be vertically disposed in the forward end of said body section and is provided with spring-pressed latch bolts indicated at 57, for engagement in suitable openings or sockets 58 in the side walls of said fixed body section. This gate may be removed and arranged between the side walls 24 of the movable body section and provide a shelf or table 85 which may also serve as an arm rest. The walls 24 are likewise provided with sockets indicated at 59, to receive the latch bolts 57.

From the foregoing description, taken in connection with the accompanying drawings, the construction, manner of operation and several advantages of my invention will be clearly and fully understood. By the provision of the adjustable body section, said section with the infant therein may be 95 raised, or elevated to any desired height above the sidewalk, so that the infant may not be disturbed in the temporary absence of the attendant. The removal of the infant from the cart or its arrangement there-in, is also rendered more convenient by the provision of such an adjustable carriage section. The device as a whole is comparatively simple in its construction, very strong and durable, and may obviously be manu- 100 factured at relatively small cost.

While I have shown and described the preferred construction and arrangement of the several elements of the device, it is to be understood that the same is susceptible of 110 considerable modification and I, therefore, reserve the privilege of adopting all such legitimate changes as may be fairly embodied within the spirit and scope of the invention as claimed.

Having thus fully described my invention, what I desire to claim and secure by Letters Patent is:

1. In a go-cart, a wheel supported frame, a body section, fixed in the forward end of said frame, a rear vertically movable body section, foldable links mounted in the frame and connected to the latter body section, means for operating said link connections to extend the same and elevate the latter body section above the fixed body section or fold said links and position the movable body section in alignment with the fixed section, and an end gate provided with means for interchangeably mounting the same in one 130

end of the fixed body section or in one end of the movable body section.

2. A vehicle of the character described including a wheel supported frame, a vertically adjustable body, a rectangular frame bar, pairs of links pivotally connected to the opposite ends of the frame bar and movable in a vertical plane with respect to said bar, the corresponding links in each pair being pivotally connected to the vehicle body and the remaining links pivotally mounted in said frame, means for positively folding the pairs of links or spreading the same apart to raise or lower the vehicle body, additional pairs of links slidably connected at one of their ends to said rectangular frame member, the other ends of said links being pivotally connected to the vehicle body and the frame respectively, and means for locking the vehicle body in its adjusted position.

3. A vehicle of the character described including a frame, spaced transverse rods mounted in said frame, a vertically adjustable vehicle body, links pivotally connected at one of their ends to said body, links

pivots mounted upon one of said shafts, a rectangular frame to which the other ends of said links are pivotally connected, additional links fixed upon the other of said shafts, corresponding links pivotally connected to the other end of said body, said latter links and the additional links being pivoted to the other end of said rectangular frame, additional pairs of links slidably connected at one of their ends to said rectangular frame, the other ends of the respective last named links being pivotally connected to the vehicle body and to the last named shaft respectively, an operating lever fixed to said shaft, a rack carried by said lever, and a pivoted dog to coöperate with the rack and hold the lever against movement, whereby the vehicle body is sustained in its adjusted position.

In testimony whereof I hereunto affix my signature in the presence of two witnesses.

GOO KON WO.
